UNITED STATES PATENT OFFICE.

PAUL GERHARDT KLINGLER AND JOSEPH W. MAYNE, OF EASTON,
PENNSYLVANIA.

MAGIC TOY.

SPECIFICATION forming part of Letters Patent No. 593,807, dated November 16, 1897.

Application filed February 26, 1897. Serial No. 625,148. (No model.)

To all whom it may concern:

Be it known that we, PAUL GERHARDT KLINGLER and JOSEPH W. MAYNE, citizens of the United States, residing at Easton, in 5 the county of Northampton and State of Pennsylvania, have invented certain new and useful Improvements in Magic Toys, of which the following is a full and complete specification, such as will enable those skilled in the 10 art to which it appertains to make and use the same.

This invention relates to toy fortune-telling devices; and the object thereof is to provide an improved device of this class, which 15 we call the "Mystic Oracle" and which is designed to answer certain questions.

The invention is fully disclosed in the following specification, of which the accompanying drawings form a part, in which the separate parts of our improvement are designated 20 by the same numerals of reference in each of the views, and in which—

Figure 1 is a central transverse section of our improved fortune-telling device; Fig. 2, 25 a section at right angles to that of Fig. 1; Fig. 3, a plan view; and Fig. 4, a section similar to Fig. 1, showing a modified form of construction.

In the practice of our invention we provide 30 a cylindrical casing 5, in which is mounted a revoluble drum 6, said drum being provided centrally with trunnions or pins 7, which pass centrally through the sides of the casing 5, and one of said trunnions or pins is 35 provided with a circular head 8, by which the drum 6 may be turned in the casing 5. The casing 5 is provided in the upper side thereof with an opening 9, and passing centrally through said drum is a rod 10, on which is 40 mounted a movable weight 11, and in the construction shown in Figs. 1 and 2 the rod 10 is provided at each end with cushions or bearings 12, which are composed of rubber or similar material, and which are designed to 45 prevent the weight 11 from striking the casing of the drum 6, and thus making a noise in the operation of the device.

In the construction shown in Figs. 1 and 2 the casing 5 and the drum 6 are preferably 50 composed of sheet metal, while in the construction shown in Fig. 4 the drum 6 is com-

posed of wood, paper, or similar material, and in this form of construction the cushions 12 are omitted.

The drum 6 in practice is provided on the 55 perimeter thereof, at the point where the ends of the rod 10 connect therewith, with the words "Yes" and "No," the word "No" being shown in Fig. 3, and by means of the head 8, which is formed on or secured to one of the 60 trunnions or pins 7, the drum 6 may be rapidly revolved, and when said drum comes to a stop one of the words "Yes" or "No" will show through the opening 9 in the top of the casing 5, it being understood that in the operation 65 of the device it is always held so that said opening will appear on the upper side thereof, and by means of this arrangement of the various parts of our device it will be apparent that any question that may be asked 70 will be answered by the device either in the affirmative or negative, the weight 11 always serving to bring one of the answers opposite the opening 9.

This device is simple in construction and 75 operation, and it will be apparent that any desired question may be asked and an answer thereto given by manipulating the drum 6, as hereinbefore described, and it will also be apparent that other answers may be placed 80 upon the drum 6 or substituted for the answers "Yes" and "No."

Having fully described our invention, we claim and as new desire to secure by Letters Patent—

1. The herein-described toy fortune-telling device, the same consisting of a cylindrical casing in which is mounted a revoluble drum, said drum being provided with a rod which passes diametrically therethrough, and on 90 which is mounted a movable weight, said drum being also provided with means for revolving the same and said casing being provided at the perimeter thereof with an opening, and said drum being provided on its 95 perimeter with words which are adapted to show through said opening, substantially as shown and described.

2. The herein-described toy fortune-telling device, the same consisting of a cylindrical 100 casing in which is mounted a revoluble drum, said drum being provided with a rod which

passes diametrically therethrough, and on which is mounted a movable weight, and said casing being provided at the perimeter thereof with an opening, and said drum being provided on its perimeter with words which are adapted to show through said opening, and means for revolving said drum, substantially as shown and described.

5 In testimony that we claim the foregoing as

our invention we have signed our names, in presence of the subscribing witnesses, this 23d day of February, 1897.

PAUL GERHARDT KLINGLER.
JOSEPH W. MAYNE.
